(57) **CLAIM**

The ornamental design for a bumper of motor vehicle, as shown and described.

DESCRIPTION

The patent or application file contains at least one drawing executed in color. Copies of this patent or patent application publication with color drawings will be provided by the Office upon request and payment of the necessary fee.

FIG. 1 is a front perspective view of a bumper of motor vehicle;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The drawings are created using computer graphics software which software inherently provides for a lightly colored hue to the otherwise black and white drawings.

Portion in pink and the lightly colored hue is shown for illustrative purposes only and forms no part of the claimed design.
